SCOURING CHAMBER FOR METAL-SCOUR-
ING MACHINES

Charles A. Dreisbach, Yonkers, N. Y., assignor to
Standard Radial Blast Corporation, Yonkers,
N. Y., a corporation of New York

Application January 22, 1943, Serial No. 473,150

2 Claims. (CL 51—8)

This invention relates to improvements in scouring-chambers and more particularly to scouring-chambers for metal-scouring machines and the like, designed for scouring to de-scale, clean, or the like, the surfaces of metal strips, sheets, wire, rods, tubing and so forth, which are ordinarily fed longitudinally through the scouring-chamber.

One object of this invention is to improve the construction set forth in my Patent No. 1,753,883, granted April 8, 1930.

Another object of this invention is to provide an improved scouring-chamber which will have a more efficient and more uniform scouring action.

With the above and other objects in view, as will appear to those skilled in the art from the present disclosure, this invention includes all features in the said disclosure which are novel over the prior art.

In the description and claims, the various parts and steps are identified by specific terms for convenience, but they are intended to be as generic in their application as the prior art will permit.

In the accompanying drawings forming part of the present disclosure, in which certain ways of carrying out the invention are shown for illustrative purposes:

Fig. 1 is a top plan view illustrating one embodiment made in accordance with the present invention;

Fig. 2 is a front elevation of Fig. 1;

Fig. 3 is a cross-sectional view on line 3—3 of Fig. 2;

Fig. 4 is a broken longitudinal sectional view on line 4—4 of Fig. 3;

Fig. 5 is a perspective view of one of the scouring-chamber plates or members;

Fig. 6 is a sectional view on line 6—6 of Fig. 5; and

Fig. 7 is a fragmental view similar to Fig. 4 of a modified construction.

Referring to Figs. 1 to 6 of the drawings showing the particular form of the invention chosen for illustration therein, the scouring-chamber 10 is mainly formed by a plurality of respective complementary upper and lower scouring-chamber plates 11 and 12 clamped together against gaskets 13 of soft rubber or other suitable material to render the joints airtight. Soft rubber gaskets are also placed between the adjacent ends of successive plates 11 and 12, and between the plates 11, 12 and the head 34, and between the head 34 and the mixing-chamber 35, to render the joints airtight. The inner faces 14 and 15 of the respective plates 11 and 12, with the inner side-faces 16

of the plates 11 and 12, define the scouring-passage 17. The faces 14 and 15 are of undulating or undulated form to respectively provide inclined abrasive deflecting-surfaces 18 and 19, which serve to deflect the granular abrasive material such, for example, as crushed chilled shot, or other suitable abrasive, toward the complementary scouring-chamber plate, and hence the abrasive is deflected toward the respective opposite surfaces of metal wires, strips, or the like 20 which are fed longitudinally through the scouring-passage 17.

The complementary scouring-chamber plates 11 and 12 are clamped together by any suitable clamping-means such, for example, as the plurality of clamping-assemblies 21, each of which includes a base clamp-member 22 and an upper clamp-member 23 pivoted thereto at 24 and being forced against the closure-plate 25 by means of a screw 26 carried in a clamp-arm 27 pivoted at 28 to the base-member 22, the closure-plate 25 engaging against gaskets 29 to provide an airtight space 30 leading from an air-inlet pipe 31 to the air-inlet openings or nozzles 32. Auxiliary clamps each formed of a bolt 43 and two opposed clips 44—44 are preferably also used to clamp the plates 11 and 12 together.

The various clamp-bases 22 may be mounted upon a main base 33 (Fig. 2). An air-and-abrasive head 34 interconnects the scouring-chamber 10 with an air-and-abrasive mixing-chamber 35 that is well known to those skilled in the art, and air or other gaseous fluid mixed with a granular abrasive is caused to pass inward through the tapered throat 36 of the head 34 and into and through the scouring-passage 17 and out the end thereof in a way that is well known to those skilled in the art. The wires, strips or other metal elements 20 may be continuously passed endwise in either direction through the machine by being pulled therethrough continuously by suitable means well known to those skilled in the art. The air and/or granular abrasive in its passage through the scouring-passage 17 acts to buoy up the metal 17 that is being scoured so that the latter may be said to more or less float without substantial contact against either the upper or lower faces or walls of the scouring-passage.

Each air-inlet pipe 31 connects with an air-inlet hose 37 which, in turn, connects to a main air-pipe or manifold 38 to supply air under pressure down through the lead-in pipes 31 to the air-openings or nozzles 32. Control-valves 45 are employed so the volume or pressure of air to

each air space 30 can be individually regulated. It will be observed that each pair of nozzles 32 at a given location occupies substantially less total width than the width of the scouring-passage, thus causing the air, which is directed in a direction generally longitudinal of the scouring-passage, to enter the scouring-chamber at a relatively-high velocity. A greater or lesser number of nozzles may be employed at the various locations, depending on the width or shape of the 10 scouring-passage 17.

By having the air-inlet openings or nozzles 32 arranged at each of a plurality of spaced-apart locations along the scouring-passage 17, a greatly-improved efficiency of scouring or cleaning of the work is obtained, both as to speed of accomplishing the same and the uniformity of the 15 scouring action. And this superior action is obtained without requiring more total air consumption than where the air enters only at one end, as a result of the fact that only a moderate-entry air pressure or velocity is needed to feed the required amount of abrasive into the entrance end of the machine. This improved construction also overcomes tendency of the granular abrasive or grit to settle or agglomerate in portions of the scouring-passage.

Instead of providing the air-inlet openings or nozzles in the upper plates, they could be provided in both the upper and lower plates, as is illustrated in Fig. 7, which is especially desirable where a wide sheet or plate of metal is to be scoured. Thus, referring to Fig. 7, a plurality of air-inlet openings or nozzles 32 in the upper plates 11 have air supplied to them through air-inlet pipes 31, all similar to the construction of the corresponding parts illustrated in Fig. 4. The lower plates 12a have air-inlet openings or nozzles 39 fed with air from air-inlet pipes 40 leading into the openings 41 in the base-clamp members 22a. By means of this construction illustrated in Fig. 7, the air and abrasive which enters through the air-and-abrasive head 34 both above and below the metal sheet 20a, is augmented above and below the sheet 20a by 45 the air entering from the nozzles 32 and 39 to thus simultaneously scour both sides or faces of the metal sheet 20a. If so desired, the air-nozzles could be omitted from the upper plates

and only the lower plates could be provided with air-nozzles. If desired, the cross-sectional shape of the scouring-passage 17 may be made with a contour to accommodate various structural shapes such, for example, as angle-irons, channels, or the like.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A scouring-device for metal-scouring machines, having an elongated undulated scouring-passage constructed and arranged to have granular abrasive introduced into one end of said passage; said device having openings at a plurality of spaced-apart locations along said passage constructed and arranged to direct gaseous fluid into said passage in a direction generally longitudinal of said passage to repeatedly accelerate the abrasive longitudinally along said passage to cause the abrasive to be repeatedly deflected against work in said passage; and separate fluid-control means for independently controlling the entry of gaseous fluid at each of said spaced-apart locations, through said openings.

2. A scouring-device for metal-scouring machines, having an elongated undulated scouring-passage constructed and arranged to have granular abrasive blown by gaseous fluid in one end of, and longitudinally along, said passage; said device having openings at a plurality of spaced-apart locations along said passage constructed and arranged to direct gaseous fluid into said passage in a direction generally longitudinal of said passage to repeatedly accelerate the abrasive longitudinally along said passage to cause the abrasive to be repeatedly deflected against work in said passage; and separate fluid-control means for independently controlling the entry of gaseous fluid at each of said spaced-apart locations, through said openings.

CHARLES A. DREISBACH.
